WINDING MACHINE WITH INDIVIDUAL DRIVING FOR THE SPINDLE UNITS

Wilhelm Reiners and Gustav Kahlisch, Munich-Gladbach, Germany, assignors to W. Schlafhorst & Co., Munich-Gladbach, Germany, a corporation of Germany

Application May 22, 1933, Serial No. 672,316
In Germany June 7, 1932

14 Claims. (Cl. 242—18)

In the arrangements for the individual electric drive as hitherto applied to winding machines, the motor was always arranged outside of the driving or yarn guiding organs. The motor therefore demanded additional room and thereby increased appreciably the floor space required for the often great number of spindle units of a winding machine.

It is true that proposals have already been made to build the motor into the interior of the bobbin carrier (bobbin supporting core) of spinning and twisting machines for rayon, and in some cases the rotary outside armature of an electric motor has been developed as a bobbin supporting core. However, this course is only possible in spinning and twisting machines for the manufacture of artificial silk, where the inside diameter of the bobbin can be made large enough so that it can take an electric motor.

The introduction of the motor inside the bobbin or its supporting core presents the drawback that the winding-on speed increases with the growing bobbin-diameter, a feature which is permissible in the case of rayon bobbins, because of the comparatively slight difference between the smallest and largest winding-on diameters, the increasing winding-on speed being therefore of no particular importance. In winding machines, however, the diameter of the bobbin tubes is kept comparatively small for the purpose of getting as much yarn as possible into given outside dimensions for the yarn mass body, thus excluding the possibility of introducing the motor into the bobbin supporting core. But even if it were possible, the difference between the inside and outside diameters of the yarn mass body and the resultant difference between the smallest and greatest yarn speeds would be inadmissible for most kinds of yarn.

The object of the present invention is the elimination of these drawbacks by introducing the motor into the interior of the body driving the body of the yarn guide or into the interior of the thread guide, instead of having it in the bobbin supporting core. It thereby becomes possible to develop the body, driving the bobbin, or the yarn guide, or the yarn guide itself into the shell of the rotary outside armature of a rotary motor. The dimensions of these parts can be made correspondingly large without thereby necessitating the slightest increase in the space required for the spindle unit, particularly as regards the spindle gauge, and without hampering in any way the normal working of the machine parts in question. The driving medium may be a motor actu-

ated by electricity, compressed air or some other gaseous fluid or liquid.

The invention is best illustrated by the following description of several embodiments thereof, taken in conjunction with the accompanying drawings, wherein

Fig. 1 is a sectional view along one of the winding units,

Fig. 2 is a front view thereof with certain parts in section,

Fig. 3 is a sectional view of another embodiment of the invention,

Fig. 4 is a front view thereof with certain parts in section,

Fig. 5 is a sectional view of another embodiment of the invention,

Fig. 6 is a front view corresponding to Fig. 5 with certain parts in section,

Fig. 7 is a sectional view of another form of construction,

Fig. 8 is a front view corresponding to Fig. 7,

Fig. 9 is a sectional view of another arrangement,

Fig. 10 is a front view of Fig. 9,

Fig. 11 is a front elevation of another embodiment of the invention embodying a positive drive of the spindle,

Fig. 12 is a sectional view along another form of the invention,

Fig. 13 is a front view, with certain parts in section, corresponding to Fig. 12,

Fig. 14 is a sectional view of a winding unit driven by compressed air, and

Fig. 15 is a front view corresponding to Fig. 14.

In the figures showing the several embodiments, 35 12 is a spindle carrying a bobbin 13 to be formed and held in a hinged holder 14. 15 is a bracket supporting the essential parts of each spindle unit. All the bearing brackets 15 of a group of units are secured to the angle iron 16 interconnecting the uprights 41. 48 is the yarn tension device, 49 the detector for the failure of an end, 20 the running-off bobbin. The creel pegs holding the running-off-bobbins are adjustably secured in known fashion to a shaft 10 which is 45 carried by the angle iron 17 connecting the bottom parts of the uprights 41.

In the embodiment shown in Figures 1 and 2, the split drum 2 serves, in known fashion, both for driving the bobbin 13 to be formed and as a yarn guide. According to the invention, the split drum 2 is driven by means of a motor 1 built into the interior of the split drum 2 rotating on shaft 9.

In order to prevent the yarn coming into con-

5

40

50

55

tact with the motor, and to permit the unimpeded lateral displacement of the yarn, a second shell 65 in the interior of the split drum encloses the motor as nearly as possible. The motor 101 may 5 be an electric motor of the usual kind with inside rotor and (outside stator), i. e. stationary field windings outside, the lengthened shaft 9 serving at the same time to carry the split drum 2. At its opposite end, the motor may be secured by a 10 flange to a corresponding face of the bearing bracket 15 which may be specially developed for the purpose. 7 is the straight yarn guiding blade which is regularly used in connection with split drums. The electric circuit intended to drive the 15 electric motor includes the contacts 50. When the creel bobbin 20 runs empty or the supply fails owing to the yarn breaking, the yarn detector 49, Fig. 1, swings to the left, its short counter-arm 49a lifts-off the contact spring 50 and thereby 20 interrupts the feed of the electric current to the motor, so that the split drum and the package 13 to be formed instantly stop, without requiring the hitherto necessary raising of the package 13 from the bobbin driving drum by mechanical 25 means. In order to put a stop to winding on to the bobbin on the desired bobbin diameter being reached, the contact spring can also be raised by means of the adjustable collar 131 of a drawbar 130 hinged to the bobbin holder 14 with its peg 132 30 and loosely projecting through a hole in the contact spring 50.

In the embodiment shown in Figs. 3 and 4, the package 13 to be formed is driven by surface friction from a winding drum 1, the shaft of which 35 is rotatably carried in a bearing bracket 15. The winding drum 1 is itself driven over the yarn guiding drum 4 the surface of which has grooves for the to-and-fro movement of the yarn guide 6 sliding on a bar 6a. The yarn guiding drum 4 is 40 designed to carry the rotary outside armature 62 of a rotary motor, the stationary inside field coils 63 of which are preferably mounted on a tube 61 secured to the bearing bracket 15, the current being fed to the motor by the wiring arranged 45 inside the tube 61. The end blocks 59 of the yarn guiding drum 4 can be made to turn on ball bearings 60 threaded on to the stationary tube 61. The operation of this embodiment is clearly 50 visible from Figs. 3 and 4. The motor inside the drum 4 drives the winding drum 1 as well as the thread guide 6; the winding drum 1, in turn, driving the bobbin 13.

In the embodiment shown in Figs. 5 and 6, a 55 hollow drum serves simultaneously as winding drum as well as yarn guide by means of the yarn guiding grooves arranged in its surface in known fashion. According to the present invention, a rotary outside armature 62 is utilized in similar fashion as the yarn guiding drum 4 in Figs. 3 60 and 4. The arrangement of the stationary inside field coils 63, the bearings of the hollow drum 3 and the feed of the current are here exactly the same as in the arrangement according to Figs. 3 and 4.

65 In the embodiment shown in Figs. 7 and 8, the split drum 2 again operates as driving means and simultaneously as the yarn guide for the package 13 to be formed. The rotary motor with its rotary outside armature 62 is fitted into the 70 special shell 65, as in the embodiments shown in Figs. 3 to 6 which show also a similar arrangement for the stationary parts of the motor, the feed of the current and the fashion of bearing the split drum.

75 In the embodiment according to Figs. 9 and 10,

the rotary motor is built into the rotary boss of a rotary wing yarn guide known in itself. Two discs 58 can be arranged at the sides of the rotary wing yarn guide, for the purpose of driving the winding drum or shaft 1 by friction or by gear- 5 ing.

The embodiment shown in Fig. 11 shows a spindle unit in which instead of the yarn mass the winding spindle is driven in known fashion. The cam 56a which carries on its surface the 10 helical groove 10 for the actuation of a yarn guide 6, carries in its interior the rotary motor described in the previously illustrated working examples. The rotary motor transmits its motion through the gearing 101e, 101d and by way of example 15 over a belt drive 101c, 101b and 101a on to the spindle 12 with the package 13 to be formed.

In the embodiment according to Figs. 12 and 13, the motor is arranged inside the winding drum or shaft 1 in exactly the same fashion as described in the embodiments shown in Figs. 3 to 10. Here, the winding drum or shaft 1 drives the bobbin 13 to be formed as also the yarn guide roller 4.

The embodiment shown in Figs. 14 and 15 show 25 a split drum 2, again for the purpose of rotating the yarn mass body or package 13 and simultaneously guiding the yarn on to the latter, but inside the drum and accurately set in the special shell 65, the electric motor is replaced by a motor 30 actuated by compressed air 70 which may be of any desired construction and which can also be replaced by one moved by some other fluid. The present working example shows a motor on the turbine principle for actuation by compressed 35 air, which is fed by pipe 71, and after actuation of the motor blades and turning the split drum, leaves the turbine through a pipe 72.

The exhaust pipe 72 or suitable branches thereof 40 can be made to guide the exhaust air to particular parts of the spindle unit where it cleans the parts in question from fluff and fly by a blowing action. The example shows for instance how the yarn guide 48 can be cleaned by the exhaust air. If in place of the compressed air some other 45 fluid is utilized as a means of actuating the motor, it is evidently necessary to provide for careful packing about the motor and the pressure piping and to guide the exhausted fluid into a common system.

50 Compressed air has been taken as an example because it is the cheapest fluid, but there is nothing in the way of using any other gaseous fluid or liquid for driving the motor.

We claim:

1. In a winding machine for winding bobbins, a winding unit, a spindle in said unit for mounting the bobbin, rotatable means mounted externally of said spindle and bobbin for guiding the thread onto the bobbin and for rotating said bobbin, and a motor within said last-mentioned means for imparting rotation thereto.

2. In a winding machine having individual drives for winding bobbins, a winding unit, a spindle in said unit for mounting the bobbin, 65 rotatable means mounted externally of said spindle and bobbin for guiding the thread onto the bobbin and for rotating said bobbin, and an electric motor within said last-mentioned means for imparting rotation thereto.

3. In a winding machine for winding bobbins, a winding unit, a spindle in said unit for mounting the bobbin, means comprising a rotatable drum mounted externally of said spindle and bobbin for guiding the thread and for rotating 75

said bobbin, and a motor within said drum for imparting rotation thereto.

4. In a winding machine having individual drives for winding bobbins, a winding unit, a spindle in said unit for mounting the bobbin, a rotatable drum mounted externally of said spindle and bobbin, a guiding channel on the periphery of said drum for guiding the thread onto said bobbin, a cylindrically shaped compartment on the inside of said drum, and a motor within said last-mentioned compartment for imparting rotation to said drum.

5. In a winding machine for winding bobbins, a winding unit, a spindle in said unit for mounting the bobbin, means comprising a rotatable member mounted externally of said spindle and bobbin for guiding the thread and for rotating said bobbin, and an electric motor mounted within said member having its rotary armature fixed upon the interior wall of said member to impart rotation to the latter.

6. In a winding machine having individual drives for winding bobbins, a winding unit, a spindle in said unit for mounting the bobbin, means comprising a rotatable drum mounted externally of said spindle and bobbin for guiding the thread and for rotating said bobbin, and an electric motor mounted within said drum having its rotary armature fixed upon the interior wall of said drum to impart rotation to the latter.

7. In a winding machine for winding bobbins, a winding unit, a spindle in said unit for mounting the bobbin, a rotatable drum having a split guiding channel on the periphery thereof for guiding the thread onto said bobbin, said drum being in contact with said bobbin to impart movement thereto, and a motor within said drum for driving said drum.

8. In a winding machine for winding bobbins, a winding unit, a spindle in said unit for mounting the bobbin, a thread guide adjacent said spindle, a rotatable drum having a guiding groove on the periphery thereof for carrying said thread guide and guiding the thread onto said bobbin, said drum being in contact with said bobbin to impart movement thereto, and a motor within said drum for driving said drum.

9. In a winding machine having individual drives for winding bobbins, a winding unit, a spindle in said unit for mounting the bobbin, a thread guide adjacent said spindle, a rotatable drum having a guiding groove on the periphery thereof for carrying said thread guide and guiding the thread onto said bobbin, said drum being in contact with said bobbin to impart movement thereto, and an electric motor mounted within said drum having its rotary armature fixed upon the interior wall of said drum to impart rotation to the latter.

10. In a winding machine having individual drives for winding bobbins, a winding unit, a spindle in said unit for mounting the bobbin, a

rotatable drum having a split guiding channel on the periphery thereof for guiding the thread onto said bobbin, said drum being in contact with said bobbin to impart movement thereto, and an electric motor having a rotary armature fixed to the interior wall of said drum for imparting movement thereto.

5

11. In a winding machine having individual drives for winding bobbins, a winding unit, a spindle in said unit for mounting the bobbin, a rotatable drum mounted externally of said spindle and bobbin and in contact with the latter, a guiding channel split in the periphery of said drum for guiding the thread onto said bobbin, a cylindrically shaped compartment on the inside of said drum and an electric motor having a rotary armature fixed upon the peripheral wall of said last-mentioned compartment for imparting rotation to said drum.

10

12. In a winding machine having individual drives for winding bobbins, a winding unit, a spindle in said unit for mounting the bobbin, a rotatable drum mounted externally of said spindle and bobbin and offset from the latter, an electric motor within said drum for imparting rotation thereto, a thread guide adjacent said bobbin, a cam groove on the periphery of said drum for controlling said thread guide, and transmission means between said drum and said spindle for rotating said spindle.

15

13. In a winding machine for winding bobbins, a winding unit, a spindle in said unit for mounting the bobbin, rotatable means mounted externally of said spindle and bobbin for guiding the thread onto the bobbin and for rotating said bobbin, an electric motor within said last-mentioned means for imparting rotation thereto, an electric circuit comprising a circuit-making device for energizing said motor, and a thread detector in each winding unit operated by the failure of thread supply to said bobbin for controlling said circuit-making device to break the circuit to said motor and to stop the winding operation.

20

14. In a winding machine for winding bobbins, a winding unit, a spindle in said unit for mounting the bobbin, a spindle support, rotatable means mounted externally of said spindle and bobbin for guiding the thread onto the bobbin and for rotating said bobbin, an electric motor within said last-mentioned means for imparting rotation thereto, an electric circuit comprising a circuit-making device for energizing said motor, and an adjusting mechanism in each winding unit for controlling the size of the wound bobbin comprising a member extending between the spindle support and said circuit-making device for controlling the latter to break the circuit to said motor at a predetermined position of said spindle support.
